Lowell Manufacturing Company.
Letters Patent No 1809-Dated Aug. 14th 1863.

~~~~~
The schedule referred to in these Letters Patent and making part of the same.

Des. 1809

Y'all whom it may concern:

Be it known that F. Cremir & Co., of Lowell, in the County of Middlesex and State of Massachusetts, have originated and designed a new Pattern for Carpets or other fabrics, of which the following is a full, clear and exact description, reference being had to the accompanying drawings, making part of this specification.

In corner A, is one fourth of a small oblong figure, with scroll outlines, resting on the figured ground, which is enclosed by a frame work of small lines and scrolls 2. Surrounding the frame 2, is the lace work 3.

The figures and surroundings of corner B are similar to those of corner A, with the exception that their position in the design is at right angles with those of corner A.

In corners 4 and 5, are grounds of diamond figures enclosed by the frames 6, respectively.

C, in the centre is a small group of leaves and acorns in outline, surrounded by the frame 8, which is overlapped by the frame 6, and the lace work of corners A and B.

The frame 9, of corner 5, is overlapped by the frame 8, also by the lace work before mentioned.

The colors employed for the different portions of the design may be varied to suit the taste and wish of the manufacturer.

~ Claim ~

What I claim as my invention, and desire to secure by Letters Patent, is: the design or pattern for carpets or other fabrics, herein set forth.
